UNITED STATES PATENT OFFICE.

ADOLPH JOH STOLT, OF MANISTEE, MICHIGAN.

PERMUTATION-LOCK.

No. 839,333.

Specification of Letters Patent.

Patented Dec. 25, 1906.

Application filed May 2, 1906, Serial No. 314,871.

To all whom it may concern:

Be it known that I, ADOLPH JOH STOLT, a citizen of the United States, residing at Manistee, in the county of Manistee and State of Michigan, have invented a new and useful Permutation-Lock, of which the following is a specification.

This invention relates to permutation-locks, and has for its object to provide a comparatively simple and inexpensive device of this character particularly designed for use as a padlock and which cannot be opened except by the owner or other person familiar with the combination.

A still further object of the invention is to generally improve this class of devices so as to increase their utility, durability, and efficiency, as well as to reduce the cost of manufacture.

With these and other objects in view the invention consists in the construction and novel combination and arrangement of parts hereinafter fully described, and illustrated in the accompanying drawings, it being understood that various changes in form, proportions, and minor details of construction may be resorted to within the scope of the appended claims.

In the accompanying drawings, forming a part of this specification, Figure 1 is a side elevation of a permutation-lock constructed in accordance with my invention. Fig. 2 is a longitudinal sectional view of the same. Fig. 3 is a perspective view of the shackle detached. Fig. 4 is a top plan view of the lock with the shackle detached. Fig. 5 is a detailed sectional view of several of the locking-tumblers disposed in superposed order. Fig. 6 is a top plan view of one of the tumblers detached, and Fig. 7 is a transverse sectional view of Fig. 6.

Similar numerals of reference indicate corresponding parts in all of the figures of the drawings.

The device consists of a base-plate 5, provided with vertically-disposed spaced sleeves or collars 6, formed with oppositely-disposed alined longitudinal slots 7 and having smooth exterior walls for engagement with the rotary tumblers 8. The tumblers 8 are preferably circular in form, as shown, and are each provided, at one end thereof with an inwardly-extending flange 9, having oppositely-disposed alined notches or recesses 10 formed therein for the purpose hereinafter referred to.

Slidably mounted within the sleeves or col-

lars 6 are the spaced legs 11 of a shackle 12, said legs being provided with oppositely-disposed teeth 13, adapted to engage the flanges 9 when the notches 14 register with the recesses 10 and the shank is partially rotated, thereby locking the shackle to the base-plate. The exterior walls of the tumblers 8 are printed, stamped, or otherwise formed with letters or symbols 15, while the upper tumbler 6' is countersunk at 16 for engagement with the lateral flanges 17 of the sleeves or collars 6, as shown, so as to retain said tumblers in position on the sleeves. The adjacent faces of the legs 11 are flat and unobstructed, while the opposite faces thereof are provided with curved bearing-surfaces 18, adapted to engage the correspondingly curved interior walls 19 of the sleeves or collars 6, whereby the legs will be guided when the shackle is moved to operative position. Secured to or formed integral with the shackle 12 are disks or collars 20, which serve to limit the downward movement of the shackle and also serve to form a housing for the sleeves or collars, so as to effectually prevent the entrance of dust, water, and other foreign matter within the sleeves. By having the legs of the shackle provided with the curved bearing-surfaces 18 said shackle may be readily reversed and introduced in the sleeves, while by reason of the disposition of the locking-teeth 13 a double gripping-surface is presented for engagement with the flanges on the rotary tumblers.

In order to release the shackle 12, the tumblers 8 are rotated until the letters or symbols forming the desired combination are arranged in alinement and in which position the locking-recesses 10 will be in alinement with each other and with the slots in the sleeves or collars, thus permitting the shackle to be readily withdrawn from said sleeves. To lock the shackle, it is merely necessary to rotate one or more of the tumblers, which causes the flanges 10 of said tumblers to engage the teeth 13, and thus prevent accidental movement of the shackle.

By forming the tumblers with one or more locking-recesses the combination may be varied, and by extending the bearing sleeves or collars and increasing the number of locking-tumblers the number of combinations may also be increased.

In some cases a single tumbler may be employed on each sleeve, and when the lock is constructed with a pivoted shackle one of the

sleeves may be dispensed with, the tumbler or tumblers being mounted for rotation on the remaining sleeve in the manner before described.

5. From the foregoing description it is thought that the construction and operation of the device may be readily understood by those skilled in the art, and further description thereof is deemed unnecessary.

10. Having thus described the invention, what is claimed is—

1. In a lock, a base-plate provided with a bearing-sleeve having oppositely-disposed aligned slots formed therein, a tumbler mounted for rotary movement on the bearing-sleeve and provided at one end thereof with an inwardly-extending locking-flange having aligned recesses adapted to register with the slots in the bearing-sleeve, and a shackle having a depending leg one wall of which is curved or rounded to conform to the interior walls of the bearing-sleeve and its opposite edges provided with spaced locking-teeth adapted to engage the locking-flange on the tumbler.

2. In a lock, a base-plate provided with spaced bearing-sleeves having oppositely-disposed longitudinal slots formed therein, a plurality of tumblers mounted for rotary movement on the bearing-sleeves and each provided at one end thereof with an inwardly-extending locking-flange having oppositely-disposed recesses formed therein and adapted to register with the slots in the bearing-sleeves, a shackle provided with spaced de-

pending legs fitting within the bearing-sleeves, teeth formed on the opposite edges of the depending legs and adapted to engage the locking-flanges on the tumblers, and collars carried by the shackle and adapted to bear against the ends of said sleeves.

3. In a lock, a base-plate provided with integral spaced bearing-sleeves having longitudinally-disposed aligned recesses formed therein, a plurality of tumblers mounted for rotation on the bearing-sleeves and each provided at the top thereof with an inwardly-extending locking-flange having oppositely-disposed recesses formed therein, the locking-flange of one of said tumblers having its upper face countersunk, a shackle provided with depending legs fitting within the bearing-sleeves and provided with spaced locking-teeth adapted to engage the flanges on the tumblers, said legs being provided with curved bearing-surfaces adapted to engage the interior walls of the bearing-sleeves, said bearing-sleeves having their terminal portions expanded laterally for engagement with the countersunk portion of the adjacent tumbler, and collars carried by the shackle and bearing against the expanded portions of the sleeves.

In testimony that I claim the foregoing as my own I have hereto affixed my signature in the presence of two witnesses.

ADOLPH JOH STOLT.
